UNITED STATES PATENT OFFICE.

KARL STEINBECKER, OF CHARLOTTENBURG, GERMANY, ASSIGNOR TO GENERAL ELECTRIC COMPANY, A CORPORATION OF NEW YORK.

PUMP.

1,119,657.

Specification of Letters Patent.

Patented Dec. 1, 1914.

Application filed January 5, 1912. Serial No. 869,625.

To all whom it may concern:

Be it known that I, KARL STEINBECKER, a subject of the King of Prussia, residing at Charlottenburg, Germany, have invented certain new and useful Improvements in Pumps, of which the following is a specification.

This invention relates to pumps, and especially to those which operate under high pressure. In such apparatus, it is necessary to inspect the working parts frequently, for purposes of cleaning or repair. Inasmuch as it is desirable not to interrupt the service of the pump for any length of time, a construction is desirable which permits a very rapid interchange of parts, or the substitution of a new pump in place of the one that is to be inspected. Ordinary pipe couplings are cumbersome and slow to take apart, especially if they are put together sufficiently tight to withstand high pressures. In order to avoid the necessity for disconnecting such couplings, the present invention provides joints which depend simply on surface contact for their tightness, and an improved quick detachable holding means for forcing said surfaces into contact and holding the parts firmly in place.

The invention comprises a pump for high pressures which is mounted in a tapered plug and a fastening or holding means for forcing the tapered plug into a socket of exactly corresponding taper, so that when thus inserted the surfaces of the plug and socket will be in close and fluid-tight contact. In the plug are formed ports which register with suitable supply and delivery passages in the walls of the socket, so that there is free communication for the fluid to flow to and away from the pump; these ports and passages coming into line as soon as the plug is seated in the socket. The holding or fastening means is arranged, as will be explained more fully hereinafter, so as to act as a lever for forcing the plug into and out of position. The removal of the plug and the insertion of a fresh one containing a pump in good order, is thus a matter of a very short time, so that the service need be interrupted but a few minutes. The apparatus herein described is intended primarily for use in supplying fuel to high compression engines and I have illustrated the same as being arranged for such use. Such pumps are required to force fuel against the very

high pressures which exist in connection with the operation of this type of engine and accordingly require very tight joints and firm holding means.

In the accompanying drawing, Figure 1 is a longitudinal section of a pump embodying my improvements, and Figs. 2 and 3 are cross sections of the same on the lines A—B and C—D, respectively.

A suitable stationary member, as for instance an integral tubular cross piece 1, connecting the side walls 2 of a reservoir 3, contains a tapering socket circular in cross section. This reservoir may take any desired form and will be at all times kept full of fluid as oil in the present instance from a suitable tank (not shown), which tank will ordinarily be so placed as to keep the reservoir constantly filled by gravity. Such arrangements are well known in connection with this type of engine and further illustration and description thereof is deemed unnecessary. A supply passage 4 connects the interior of the reservoir with said socket, and a delivery passage 5 leads from said socket to a delivery pipe 6, which is tightly connected with said passage 5 by a union 7, of well-known construction.

A plug 8 fits snugly into the socket and is provided with a central bore in which is a bushing 9 which is counterbored for a portion of its length. A pump rod and plunger 10 has a sliding fit in said bushing, being shouldered at 11 to fit the counterbore thereof. The annular space 12 around the plunger above this shoulder constitutes the working or suction chamber of the pump, the shoulder serving as an annular piston. The lower or suction end of this chamber 12 connects by a port 13, Fig. 3, with the inner end of the supply passage 4, being provided with a partially circumferential groove 14 on the outer surface of the plug to enable the port to be registered with the passage without the necessity of great exactness as to the angular position of the plug in the socket. A spring-seated valve 15 controls the flow of fluid through the passage 4 and port 13 to the chamber 12, said valve opening inwardly toward said chamber. At the upper end of said chamber a port 16 communicates with the delivery passage 5, by means of a partially circumferential groove 17 on the outside of the plug 8, arranged to register with the inner end of said passage when the plug 110

is seated. An outwardly opening spring-seated valve 18 controls the port 16.

The central bore through the plug is counterbored at its lower end to form a 5 housing for a helical spring 19 which encircles the lower end of the bushing 9 and abuts at its lower end upon a collar 20 at the lower end of the pump plunger, and biases said plunger downward. An antifriction 10 roller 21 is journaled in the forked end of said plunger and rests upon a cam 22 which effects the upward or forcing stroke of the pump. This cam is carried by cam shaft 22^a which may be the cam shaft of the engine. 15 The spring 19 returns the plunger after the cam has acted, and effects the suction stroke. The counterbored portion of the plug may have a lining 23, if desired, to afford a wearing surface and guide for the roller and collar. 20 This lining may be removably retained in place by an annular cap 24 screwed upon the lower end of the plug.

In order to hold the plug firmly in its socket and yet to permit of its ready removal when desired, a yoke 25 is provided, 25 one end of which engages with a recess in a lug 26 on the member containing the socket. At some intermediate point the yoke engages with recesses in the sides of the plug, while 30 its other end has an eye through which extends the shank 28' of a wing nut 28. This wing nut is threaded on to a screw-threaded stud 27 and is provided with flanges or shoulders 29 and 30 between which rests the 35 end of the yoke 25 that has the eye. By this arrangement it will be seen that the one end of the yoke carries the wing nut 28 and can be forced in either direction by simply turning the same. When it is desired to 40 move the plug to permit the pump to be inspected or repaired, it is simply necessary to unscrew the wing nut, by which operation the yoke acts as a lever to pull the pump from its seat, the lug 26 being the fulcrum. 45 A substitute plug and pump can then be quickly inserted and forced firmly into the socket by screwing down the wing nut 28, the whole operation taking but a few minutes. To prevent the escape of the fluid 50 from the reservoir while the pump plug is being removed, the upper end of the supply passage 4 may be located above the normal level of said fluid; or if it has to be below

said level, a suitable shut-off cock can be inserted in said passage. By the use of this 55 specific quick detachable fastening means I provide a leverage arrangement whereby I can bring a large amount of power into play for forcing the pump into the socket and removing the same for I have the advantage 60 of both the lever and the inclined plane of the screw.

In accordance with the provisions of the patent statutes, I have described the principle of operation of my invention, together 65 with the apparatus which I now consider to represent the best embodiment thereof; but I desire to have it understood that the apparatus shown is only illustrative, and that the invention can be carried out by other 70 means.

What I claim as new and desire to secure by Letters Patent of the United States, is,—

1. The combination of a reservoir containing a seat, a removable plug fitting liquid-tight to the seat and carrying a pump, and a quick-detachable fastening holding the plug to the seat, said fastening means comprising a pivoted lever engaging with the plug for positively moving the same in either direction, a screw-threaded stud, and a nut carried by the lever and adapted to engage the screw-threaded stud. 75

2. The combination of a reservoir having a tapered seat, a plug making a liquid-tight joint therewith, a pump carried by the plug, a yoke embracing the plug and pivoted at one end, and a wing nut carried by the other end of the yoke for securing the same in place, as described. 80

3. The combination of a vessel for containing a supply of oil, said vessel having a tapered seat in the wall thereof, a pump provided with a plug fitted to the seat and making an oil-tight joint therewith, a yoke engaging with the plug for forcing it into and from its seat, the yoke pivoted at one end and at the other carrying a threaded nut, and a threaded stud for the nut. 95

In witness whereof, I have hereunto set 100 my hand this fourteenth day of December, 1911.

KARL STEJNBECKER.
